UNITED STATES PATENT OFFICE.

JOHN G. WHILLDIN, OF PHILADELPHIA, PENNSYLVANIA.

DESIGN FOR A FLOWER-POT.

SPECIFICATION forming part of Design No. 19,406, dated November 5, 1889.

Application filed October 12, 1889. Serial No. 328,850. Term of patent 7 years.

To all whom it may concern:

Be it known that I, JOHN G. WHILLDIN, a citizen of the United States, and a resident of Philadelphia, in the county of Philadelphia and State of Pennsylvania, have invented 5 certain new and useful Designs for Flower-Pots; and I do declare the following to be a full, clear, and exact description of the invention, such as will enable others skilled in the art to which it appertains to make and use 10 the same, reference being had to the accompanying drawings, and to letters or figures of reference marked thereon, which form a part of this specification.

15 Figure 1 of the drawings is a representation of this invention, and is a side view. Fig. 2 is a bottom view.

This invention has relation to designs for 20 flower-pots; and it consists in the novel form and configuration of parts, as hereinafter set forth.

In the accompanying drawings, the letter A designates the body portion of the pot, which

is of the form of a frustum of a cone, surrounded by a re-enforced marginal portion or 25 offset B, of cylindrical or nearly cylindrical shape, and terminating below in the corrugated bottom C, consisting of the angular tapering ribs d and the intervening rounded depressions e, both ribs and depressions extending up a short distance on the wall of the body portion and radially toward the central aperture g in the bottom of the pot, as shown.

What I claim is—

The design for flower-pots, consisting of the 35 conical body portion having the surrounding enlargement b, and terminating below in the corrugated bottom, having the angular tapering radial ribs d and intervening rounded depressions e, as shown and described. 40

In testimony whereof I affix my signature in presence of two witnesses.

JOHN G. WHILLDIN.
